Fig. 5.

The drawing illustrates a mechanical assembly, possibly a clutch or brake mechanism. It features a central circular component (30) with a slot, surrounded by a housing (31). A lever system is attached to the housing, with a main lever (41) and a connecting rod (43). A spring (35) is positioned between the main lever and a side lever (42). A pin (44) is located on the side lever. A plate (37) is secured to the housing. A rod (46) is attached to the side of the housing. A small circular component (39) is also shown. The assembly is mounted on a base (50) which includes a slot (51) and a stepped structure (52). A label 'Fig. 8.' is present on the left side of the drawing.

UNITED STATES PATENT OFFICE.

ERASTUS EDWIN KING, OF CENTERTON, ARKANSAS.

SMELTER.

Application filed June 1, 1922. Serial No. 565,030.

To all whom it may concern:

Be it known that I, ERASTUS EDWIN KING, a citizen of the United States, residing at Centerton, in the county of Benton and 5 State of Arkansas, have invented a new and useful Smelter, of which the following is a specification.

This invention has reference to smelters, and more particularly smelters for extracting precious metals, such as gold and silver from ores taken from mines containing such metals.

The primary object of the invention is to provide a smelter heated by oil burners, the 15 smelter having a novel arrangement of pipes providing communication between various chambers and elements of the smelter making it possible to refine or extract the ores to the finest degree.

Another object of the invention is to provide a smelter wherein the body portion thereof may be readily and easily opened to facilitate repairing and cleaning of the burners as well as the ore chamber thereof.

A still further object of the invention is to provide means for readily and easily conveying the slag or other material held in the ore chamber to facilitate cleaning of the ore chamber.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a smelting furnace constructed in accordance with the present invention.

Figure 2 is a side elevational view thereof.

Figure 3 is a sectional view taken on line 3-3 of Figure 1.

Figure 4 is a sectional view taken on line 4-4 of Figure 1.

Figure 5 is a sectional view taken on line 5-5 of Figure 4.

Figure 6 is a sectional view taken on line 6-6 of Figure 3.

Figure 7 is an elevational view disclosing the bearing supporting means for the spiral conveyor.

Figure 8 is a sectional view on line 8-8 of Fig. 2.

Figure 9 is a sectional view on line 9-9 of Fig. 2.

Figure 10 is a sectional view taken on line 10-10 of Figure 1, the lower portion of the furnace being removed.

Referring to the drawings in detail, the reference character 5 designates the base of the smelting furnace which is formed with 60 a passageway 6, the upper wall thereof being formed with an opening 7 to permit material to be discharged into the passageway 6, where the same may be removed. Extending transversely of the bar 5, are 65 the partitioning walls 8 providing a passageway 9 to admit air to the central portion of the smelter and feed the burner 10 positioned thereabove. A pipe 11' is shown as providing communication between the passageway or flue 9 and the burner chamber 12. Supported adjacent to one end of the passageway 9 is a hinged closure 13 for controlling the passage of air into the passageway 9.

A wall 14 is formed at one end of the passageway 9 and separates the passageway 9 from the flue 15, which flue 15 provides communication between the upper portion of the smelter and smoke stack not shown, 80 for directing the heat from the smelter downwardly and to the chimney.

The body portion of the smelter is indicated at 16, the same being formed with a central circular portion provided with partitioning walls 17 which divide the body portion into a plurality of adjacent burner chambers 18, one of the walls 17 however being relatively wide and formed by opposed sections 19 to provide a passageway 20 communicating with the atmosphere through an opening 21 formed in the wall of the body portion to admit air above the burners to be hereinafter more fully described.

Burners 22 are positioned in the burner chambers 18, the burners including burner pipes 23 and feeding pipes 24, the burner pipes being disposed adjacent to the bottom of the body portion, so that the heat 105 therefrom will pass upwardly to heat the ore chamber 25 supported thereabove. Disposed substantially centrally of the body portion 16 is a circular wall 26 forming a central burner chamber 12 in which is po- 110

sitioned the burner 10 that is circular in formation and embraces the pipe 11 that feeds air to the burner chamber. The upper extremity of the wall 26 is serrated as at 5 27 providing openings between the wall and base of the ore chamber to permit the heat from the central burner 10, to pass outwardly therefrom.

The walls 17 extend inwardly, the inner 10 surfaces thereof contacting with the circular wall 26, the portions of the walls above the circular wall 26 being cut away to accommodate the ore chamber 25, which is shown as positioned therein. This ore 15 chamber is formed with an opening 28 adjacent to the bottom thereof, in which opening is positioned the tubular member 29 that is disposed at an angle with respect to the base 5 and extends through the body 20 portion of the smelter. Positioned in the tubular member 29 is a spiral conveyor 30 which is of a length to extend into the ore chamber 25, the opposite end thereof being provided with a gear 31 adapted to 25 mesh with the pinion 32 of the shaft 33, whereby rotary movement of the shaft will produce a relative movement of the spiral conveyor to feed material from the ore chamber to accomplish the cleaning thereof. 30 The material fed through the tubular member 29 is deposited through the opening 34 and into the passageway 6, where the same will be removed.

Supports 35 are mounted on the base 35 and carry bearing members 36 at the upper ends thereof, which bearing members accommodate the supporting shaft 37 which is shown as having its ends disposed in the bearings. This shaft 37 provides a 40 support for the hangers 38 in which the shaft 33 is mounted, pulleys 39 being secured to the shaft 33 for imparting rotary movement thereto.

From the foregoing it will be seen that 45 due to this construction, the shaft 37 may be rotated or swung to bring the pinions 31 and 32 into engagement with each other. In order that the shaft 37 may be moved as described, a controlling handle 40 is carried 50 by the shaft, a suitable latch member 41 being provided to contact with the handle 40 to hold the same in its normal or inactive position.

The tubular member 29 is so constructed 55 that the same may be moved within the opening 28 to bring the same into operation. Guide rods 42 are mounted on opposite sides of the supports 35, the guide rods being arranged in pairs so that the 60 bars 43 may move therebetween to guide the tubular member together with the spiral conveyor, to and from the opening, and at the same time provide means to permit the tubular member 29 and member 65 30 to be moved into and out of operation.

When the tubular member 29 is in its inactive position, the opening 28, in which the same is positioned, is closed by a suitable plug, not shown, which may be readily withdrawn from the opening, when it is 70 desired to position the tubular member 29. Latch members 41' are pivotally supported adjacent to the bars 43 to hold the bars 43 and member 29 to which the bars are connected, in their active positions. 75

The reference character 44 designates an air supply pipe which has connection with a suitable air blast pipe not shown, as through the coupling 45. As shown, this pipe 44 extends around approximately the 80 entire base 5, the same being spaced however from the body portion.

Above the pipe 44 is disposed the main oil supply pipe 46 which has communication with the burners 22 as through the 85 relatively short pipes 47, suitable valve members 48 being provided for controlling the passage of the oil or liquid fuel to the burners 22.

Air is supplied to the pipes 47, through 90 the pipes 49 which communicate with the pipe 44, and pipes 47 so that as the air is forced through the pipes, particles of the liquid fuel are picked up and carried to the burners proper. Valve members 50 control the passage of the air blast to the 95 pipes 47. An oil supply pipe 51 is also in communication with the main oil supply pipe, and feeds fuel to the burner 52 which is positioned within the ore chamber to 100 supply heat directly to the ore contained in the chamber.

Supported on the body portion 16, and housing the ore chamber 25 is an upper casing 53 which embodies hinged sections 105 mounted on the supporting rod 54 which is secured to the base 5, in any suitable manner and held against lateral movement by means of the cables 55. Straps 56 are carried by the respective sections of the 110 casing 53 and embrace portions of the rod, as clearly shown by Figure 2 of the drawings.

Apertured ears 57 are formed on the 115 respective sections of the casing, which ears accommodate the bolts 58, whereby the sections may be moved into close engagement with each other to completely house the ore chamber.

As shown, the upper casing 53 is formed 120 with lateral openings 59 and 60 respectively, which openings are closed by means of the hinged closures 61 whereby a person may readily and easily view the interior of the ore chamber 25 to inspect the same for 125 repairs or cleaning purposes.

An opening 62 is formed in the upper wall of the ore chamber and disposed directly under the opening 63 formed in the upper wall of the upper casing 53, the 130

openings 63 being provided to admit material to the ore chamber. Positioned on the upper casing 53 is a housing 64 which is formed with a hopper 65 extending from one of the side walls thereof, which hopper has the lower portion thereof communicating with the opening 63 whereby ore may be fed through the hopper to the ore chamber. Operating in the opening 63 is a sliding valve member 66, which, when in its lowermost position lies within the opening 63 to close the same for controlling the passage of the ore through the openings 62 and 63.

A housing 67 accommodates the valve member 66 and is formed with an opening 68 to permit the valve rod 69 to move therethrough, the valve rod 69 having connection with the valve member 66 as clearly shown by Figure 3 of the drawings.

An operating lever 70 is pivotally supported on the housing 64 and connects with the valve rod 69 so that the valve member 66 may be moved as described, at the will of the operator. Formed on the outer surface of the ore chamber 25 are ribs 71 which contact with the inner surface of the upper housing 53 to support the housing in spaced relation with the ore chamber, to allow for the free passage of heat around the ore chamber to

properly heat the same.

A partitioning member 73 is positioned in the housing 64 and is supported in spaced relation with the bottom thereof to provide a passageway therebetween, the partitioning member 73 being formed with lateral openings 74 to provide means of communication between the upper portion of the housing 64 and space between the partitioning wall 73 and bottom wall of the housing.

Positioned in the housing and supported by the partitioning member 73 is a hopper 75 which is formed with a lower compartment 76 to accommodate the sliding container 77 which has a knob 78 to permit the container 77 to be removed. Communicating with the upper portion of the ore chamber 25 is a pipe 78' which has its upper extremity communicating with the hopper 75, whereby products of combustion may pass from the ore chamber into the hopper 75. The container 77 is designed to contain a quantity of mercury for collecting the metals which may pass from the upper portion of the ore chamber and be otherwise lost.

Covering the upper portion of the hopper 75 is a member 79 which is also formed with lateral openings 80 providing communication between the compartment formed between the member 79 and upper wall 81 of the housing establishing a cooling space around the hopper and container supported at the base thereof.

Extending through the member 81, is a pipe 82 which is in communication with a

suitable source of water supply to cause a circulation of the water around the hopper and container 77 to cool the same.

In order that the hopper 75 may be efficiently cleaned, a pipe 84 is provided, which pipe has communication with the hopper 75 permitting access to the hopper to allow an operator to insert a suitable tool to clean the hopper 75. A closure 83 closes the upper end of the pipe 84 to normally close the upper end and prevent material from falling thereinto. Cut out portions 85 are formed at the base of the housing 64 at opposite sides thereof to permit air to pass under the housing to further cool the walls thereof.

Above each burner chamber is an opening 86 which is closed by a sliding closure 87 to permit a person to view the burners positioned within the burner chambers to repair or adjust the same. A discharge opening 88 communicates with the ore chamber 25 for receiving material therefrom, a suitable discharge pipe 89 being provided for carrying off the material. The pipe 89 is normally closed as by means of the removable plug 90, whereby the operator may at predetermined intervals allow the molten metal to drain from the ore chamber 25.

In order that the tubular member 29 may be readily moved to its operative or inoperative position, a lifting lever 91 is provided, the same being pivotally supported adjacent to the forward supporting member 35, whereby the extremity 92 thereof lies directly under the tubular member 29 for lifting the tubular member.

It might be further stated that the container 77 is formed with an opening 93 whereby material passing into the container may overflow and pass outwardly through the pipe 94 that is shown as having one end thereof communicating with the compartment 76.

The operation of the device is as follows:

The several burners are supplied with fuel in a manner as described and when the ore chamber has become properly heated, ore is discharged into the ore chamber where the metals contained therein are melted. The molten metal collects in the base of the ore chamber and at intervals is released through the pipe 89 and deposited in suitable containers not shown.

The metals which are present in the products of combustion and vapor arising from the heated ore in the ore chamber pass upwardly through the pipe 78' and into the hopper 75 where the same pass downwardly, contacting with the mercury in the container 77 to further separate any particles of metal.

During the smelting operation, cooling fluid passes through the pipe 82 circulating around the hopper 75 and container 77 to

the end that the smelter is maintained in a cooled condition, to properly carry out the purpose of the device.

If it is desired to clean the ore chamber, the tubular member 29 may be inserted in the opening 28, whereupon the member 37 may be swung downwardly to bring the gears 31 and 32 into mesh. It is obvious that as power is applied to the pulleys 39, 10 the spiral conveyor 30 is rotated, carrying the dust, hardened rock and slag from the ore chamber where the same is deposited in the passageway 6 as previously described.

As the smelting operation continues the 15 valve member 66 may be operated to discharge predetermined quantities of ore replenishing the quantity in the ore chamber 25.

Having thus described the invention, 20 what is claimed as new is:

1. In a smelting furnace, a base, a body portion supported on the base, said body portion having a plurality of burner chambers, burners in the burner chambers, 25 an externally heated ore chamber supported above the burner chambers to receive heat therefrom, a circular wall disposed centrally of the body portion, a central burner positioned in the compartment formed by the 30 circular wall, said circular wall having cut out portions to permit heat to pass therefrom, a housing surrounding the burner chambers and disposed in spaced relation therewith to permit heat to circulate around the ore chamber, means for supplying ore 35 to the ore chamber, and means for draining metals from the ore chamber.

2. In a smelting furnace, a base, a body portion supported on the base, a circular 40 wall providing a central burner chamber, an externally heated ore chamber supported above the circular wall to receive heat therefrom, means for delivering ore 45 to the ore chamber, means positioned above the ore chamber for treating the vapor therefrom, and means for draining molten metal from the ore chamber.

3. In a smelting furnace, a base, a body portion supported on the base and having 50 burner chambers, an externally heated ore chamber supported above the burner chambers to receive heat therefrom, a removable spiral conveyor operating in the base of the ore chamber for removing material there- 55 from, means for operating the spiral con-

veyor, means for enclosing the upper portion of the ore chamber, means for feeding material to the ore chamber, and means for draining metals from the ore chamber.

4. In a smelting furnace, a base, a body portion supported above the base, burner chambers formed in the body portion, burners within the burner chambers, an externally heated ore chamber supported above the burner chambers to receive heat 65 therefrom, a sectional housing enclosing the upper portion of the ore chamber, the sections of the housing being hingedly connected to permit the ore chamber to be exposed, means above the ore chamber for receiving vapors therefrom, to extract metals from the vapors, means including a hopper and valve member for feeding material to the ore chamber, a heating means within the ore chamber, and means for draining molten 70 metals from the ore chamber.

5. In a smelting furnace, a base, a body portion supported by the base, an externally heated ore chamber having one end thereof disposed within the body portion, partitioning walls in the body portion for supporting the ore chamber, the spaces between the partitioning walls providing burner chambers, burners within the burner chambers, a central burner for heating the 85 central portion of the ore chamber, means for treating the fumes arising from the ore chamber, means for feeding material to the ore chamber, and means for draining molten metals therefrom. 90

6. In a smelting furnace, a base, a body portion on the base, an externally heated ore chamber supported by the body portion, means in the body portion for heating the ore chamber, a sectional housing embracing the upper portion of the ore chamber and being spaced therefrom to provide a heat passageway around the ore chamber, means disposed within the ore chamber for directly heating the contents thereof, mean for feeding ore to the ore chamber, and means for draining molten metal therefrom. 95 100

In testimony that I claim the foregoing as my own, I have hereto affixed my signature in the presence of two witnesses.

ERASTUS EDWIN KING.

Witnesses:

R. W. MILLER,
F. C. HUGHES.
